UNITED STATES PATENT OFFICE.

JESSE A. MAY, OF SPRINGFIELD, KENTUCKY, ASSIGNOR OF ONE-EIGHTH TO R. C. BOTTOM AND ONE-EIGHTH TO J. Q. MILTON, BOTH OF MACKVILLE, KENTUCKY, ONE-EIGHTH TO J. E. BROWN, OF HARRODSBURG, KENTUCKY, AND ONE-EIGHTH TO J. T. SKEINS, OF SPRINGFIELD, KENTUCKY.

RAILWAY-GATE.

1,298,537.

Specification of Letters Patent. Patented Mar. 25, 1919.

Applicant Filed March 15, 1918. Serial No. 222,874.

To all whom it may concern:

Be it known that I, JESSE A. MAY, a citizen of the United States residing at Springfield, in the county of Washington and State of Kentucky, have invented new and useful Improvements in Railway-Gates, of which the following is a specification.

This invention relates to improvements in railway gates and operating mechanism therefor, the object of the invention being to provide electrical operating means for closing the gates at a railway crossing on the approach of a train, the mechanism being so arranged that as the train nears the crossing the gates will be lowered to approximately horizontal position and will remain down until the train has passed after which the gates will be raised to open the crossing road for traffic.

20 A further object of the invention is to provide means to cause one of the gates to be operated by the other.

With the above and other objects in view the invention consists in the construction, combination and arrangement of devices hereinafter described and claimed.

In the accompanying drawing:—

Figure 1 is a perspective view of a railway crossing gate constructed and arranged in accordance with my invention.

Fig. 2 is a detailed elevation of the same, partly in section.

Fig. 3 is a similar view of the same at right angles to Fig. 2.

Fig. 4 is a detail sectional view showing the solenoid and its connection.

Fig. 5 is a detail perspective view of the contact rail.

In the drawing the tracks of a railroad are indicated at 1 and a public street or road is indicated at 2, intersecting the railroad tracks. Near the street or road and at opposite sides of the railroad tracks are posts 3—4. Crossing gate arms 5 and 6 are respectively pivotally mounted at the upper end of the posts as at 7 and 8 and each gate arm is provided at its shorter end with a weight 9, the said weights being sufficient to normally raise the gate arms and hold them in an elevated position to clear and leave the public road or street clear at the

crossing. The gate arms 5 operate and control the gate arm 6, said gate arms being connected together by a cable 10 which passes under the railway track and passes 55 under direction pulleys 11 which are mounted near the lower end of the posts. One end of the cable is attached to the gate arm 5 at a point between the pivot 7 and the inner end of the said gate arm. The other 60 end of the cable is attached to the gate arm 6 at a point between the pivot 8 and the outer end of the said gate arm. Hence when the gate arm 5 is lowered its inner end in moving upwardly causes the cable to also 5 lower the gate arm 6, as will be understood, both of the gate arms thus operating simultaneously and the gate arm 6 being actuated by the gate arm 5.

The gate arm 5 is connected by a link 12 70 to the armature 13 of a solenoid 14. The winding of the solenoid is connected to earth and also to one end of the contact rail 14', said contact rail being arranged between the track rails 1 and being of sufficient 75 length and extending across the roadway 2. In practice, the contact rail is cross-sectionally triangular and is secured at suitable spaced points on the upper end of short posts 115, which posts are driven in the 80 ground and serve to support the contact rail and also to insulate the same as will be understood.

Each locomotive is provided with a circuit closer fork 15, which is insulated as at 85 16, which is electrically connected, as at 17 to one pole of a battery or generator 18, carried by the locomotive, the other pole of which is connected to the metal frame of the locomotive and is hence grounded. The circuit closer fork is so arranged and located on the locomotive as to come in contact with the contact rail 14' as the locomotive approaches from either side. This completes 90 an electric circuit from the battery or generator through the fork, the contact rail and the winding of the solenoid, so that the solenoid is energized and the gate arm 5 lowered thereby and caused to extend across a road or street 2. The gate arm 6 being connected 100 to the gate arm 5 by the cable, as hereinbefore described, is also simultaneously low-

ered, so that the crossing is protected at both sides. Owing to the length of the contact rail the circuit remains closed and the gates are held in closed position until the 5 train has safely passed the crossing. As the contact or circuit closing fork leaves the contact rail, the electric circuit is broken, and thereupon the weights serve to automatically raise the gate as will be understood. 10 An electric light and a signaling bell or annunciator 20 may also be included in the electric circuit, to indicate by the light and also by the sounding of the bell, when the gates are closed, and thus contribute to 15 avoid accident at the crossings.

While I have herein shown and described a preferred form of my invention, I would have it understood that changes may be made in the form, proportion and construction of 20 the several parts without departing from the spirit of my invention and within the scope of the appended claim.

Having thus described my invention I claim:—

In combination with a pair of railway crossing gates pivotally mounted for vertical movement, weights to raise the gates, a cable connecting the gates, the ends of the cable being attached to the respective gates at points spaced from opposite sides of the 30 respective pivots of the gates so that one of the gates is lowered by the other, a solenoid, a link connecting the armature of the solenoid to the last named gate, a contact rail extending across and beyond opposite sides 35 of the crossing and being independent of and disconnected from the track rails and being electrically connected to the winding of the solenoid, and a train carried circuit closer to contact with the contact rail and arranged in contact therewith by moving from end to end thereof.

In testimony whereof I affix my signature.
JESSE A. MAY.
